BATTERY TERMINAL OR LIKE PULLER

Arthur P. Stone, Akron, Ohio, assignor to The Wright Tool and Forge Company, Barberton, Ohio, a corporation of Ohio

Application August 2, 1940, Serial No. 349,589

6 Claims. (Cl. 29—85)

This invention relates to a pulling tool, and in particular relates to a tool for pulling split terminals from battery posts.

A purpose of this invention is to provide a simple, compact, and relatively inexpensive puller of the character described, having sufficient power for removing the usual split terminals from battery posts, as for example, when the terminal connections have become so corroded that loosening the terminal clamping nut is ineffective to loosen the terminal from the post.

Another object of the invention is to provide a tool of the character described, capable of applying sufficient clamping pressure on the sides of the terminal for removing the terminal from its post, this being particularly useful when the terminal is so close to the battery top that the hooked gripping elements of the usual pulling tools cannot be engaged under the lower edge portions of the terminal.

Still another object of the invention is to provide a tool of the character described which is easily and quickly adjustable to accommodate battery terminals or the like of a wide range of sizes.

These and other objects of the invention will be manifest from the following brief description and the accompanying drawing.

Of the accompanying drawing:

Figure 1 is a side elevation, partly broken away and in section, of a battery terminal tool embodying the invention, the same being shown in operative position for removing a terminal connection from a battery post.

Figure 2 is an edge view of the tool shown in Figure 1.

Figure 3 is a cross-section taken on line 3—3 of Figure 1.

Figure 4 is a front elevation, similar to Figure 1, illustrating another embodiment of the invention.

Figure 5 is an edge view, partly broken away and in section, of the tool shown in Figure 4.

Referring particularly to Figures 1, 2 and 3 of the drawing, the numeral 10 designates a cross-member having a central bore 11 for rotatably receiving an internally threaded nut or sleeve 12, the latter having an enlarged portion or collar 13 at one end thereof for abutment with one side of cross-member 10. The nut or sleeve 12 is held against relative axial movement in the bore 11 by means of a split ring 14 retained in an annular groove 12a in nut or sleeve 12, and engaging the side of the cross-member opposite to said collar 13 of the nut. Nut 12 is provided

with a suitable handle 15 on the outer end thereof for turning the same relative to cross-member 10, for purposes to be described.

A pressure post 16 may have a stem portion 17 adjustably threaded into the nut 12, the end of the post extending axially outwardly of the nut and being flattened, as shown, and provided with a longitudinally extending slot 18 for axially slidably, but non-rotatably receiving a squared pivot element therethrough. Element 19 has integral pivot pins 20, 20, extending outwardly from opposite ends thereof, upon which pins may be pivoted a pair of oppositely disposed gripping elements 21 and 22, these elements being arranged in crossed relation to provide opposed jaws 21a and 22a, for engagement with opposite sides of the usual split terminal T of a battery post P. Extensions 21b and 22b of the crossed gripping elements 21 and 22, may extend angularly outwardly of the post 16 toward cross-member 10 to swing in arcs about the pivot pins 20. Links 23 and 24 may be pivoted at one end thereof to oppositely disposed lugs 25 and 26 on cross-member 10, and pivoted at the other end thereof, as indicated at 27, 28, to the outer ends of the extensions 21b and 22b, thereby providing a double toggle connection between the cross-member and the gripping elements. The arrangement is such that the pivot element 19 may be freely moved in the slot 18 toward and from the cross-member 10, to open and close the jaws 21a and 22a, independently of adjustment of post 16 relatively of said cross-member.

In the use of the tool described, the nut or sleeve 12 is rotated in the bore 11 of cross-member 10, axially to adjust the post 16 relatively of the cross-member, so that said post will be in an approximate position for engagement of the outer end thereof with the end of the battery post 40 P, and yet permit the pivot element 19 to be moved in the slot 18 from the position shown in chain-dotted lines in Figure 1, for example, to the full-line position thereof in which the jaws 21a and 22a will be in engagement with diametrically opposite sides of a battery terminal T. While trial adjustments of pressure post 16 are being made, the pivot element 19 may be slid back and forth along the slot 18 by engaging the hand over the handle 15 and grasping opposite ends of pivot element 19 with the thumb and forefinger, for example, whereby the gripping element may be freely opened and closed, as indicated in full and chain-dotted lines in Figure 1.

When the approximate adjustment of the tool has been found, substantially as shown in full

lines in Figure 1, handle 15 is rotated in the proper direction while the end of the pressure post 16 is held against the end of the battery post P, thereby urging cross-member 10 outwardly of post P and tending to straighten the toggle connection between the cross-member 10 and the gripping elements 21 and 22 to clamp the jaws 21^a and 22^a against the opposite sides of the terminal T. Although the tool described is compact in construction, the double toggle connection between the cross-member and the gripping elements produces a mechanical advantage in the gripping jaws 21^a and 22^a, such that sufficient pressure may be applied between opposite sides of the terminal T to permit pulling the terminal from the battery post P, when the connections are so corroded, for example, that loosening the clamping bolt on the terminal has no effect to loosen the terminal from the battery post. This side pressure action of the gripping jaws is particularly advantageous in situations where the terminal T is so close to the top of the battery that the gripping elements cannot be engaged under the bottom edge of the battery terminal.

Referring to Figures 4 and 5, which show a modified form of the invention, the numeral 30 designates a cross-member having threaded therethrough a pressure post 31, the latter having a suitable handle 32 for turning the post relative to the cross-member. The end of the post 31 remote from handle 32 may have a reduced portion 33, rotatably and slidably received through a bore 34 in a pivot block 35, said block being axially shiftable on the reduced portion of the post toward and from the cross-member 30. A coil spring 36 may be arranged between block 35 and member 30 for normally yieldingly urging the block 35 away from cross-member 30. Integral with the block 35 may be oppositely disposed pivot pins 37, 37, on which are pivoted in crossed relation a pair of gripping elements 39 and 40, having inwardly projecting gripping toes 39^a and 40^a, adapted to engage against the lower edges of a battery terminal T' for removing the same from the battery post P'. The gripping elements 39 and 40, if desired, may be provided with gripping jaws similar to the jaws 21^a and 22^a of Figure 1.

The crossed extensions 39^b and 40^b of the gripping elements 39 and 40, respectively, may extend outwardly at an angle to the post 31, toward the cross-member 30. Links 43 and 44 may be pivoted at one end to oppositely disposed lugs 45 and 46 on cross-member 30, and pivoted at the other end thereof, as indicated at 47 and 48, to the ends of the extensions 39^b and 40^b. This provides a double toggle arrangement between the cross-member 30 and the gripping elements 39 and 40, whereby the pivot block 35 is freely yieldingly shiftable along the reduced portion of the pressure post 31 toward and from the cross-member 30, independently of relative axial movement of the cross-member on the pressure post 31 obtained by rotating the post 31 relatively of the cross-member.

The outer ends of the pivot pins 37, 37, may have squared extensions 73^a, 73^a, adapted to be received through similarly squared openings in downwardly extending flanges 49, 49, of a pair of oppositely disposed finger grips 50, 50, which extend outwardly from the gripping elements 39 and 40, on opposite sides of the tool, the ends of the pivot pins 33 being peened over to retain flanges 49 in loose engagement with the sides of

the respective gripping elements 39 and 40 to permit free pivotal movement thereof. This construction is such that the finger grips 50, 50 remain in the same angular position relative to the block 35 as the latter is slid along the reduced portion 33 of post 31, whereby the jaws of the gripping elements may be opened and closed against the action of a spring 36 by hooking the thumb over the handle 32 or the end of the post 31, and hooking the second and third fingers of the hand under the finger grips 50, 50, so that the jaws of the gripping element may be opened or retained in open position by applying a squeezing action of the hand.

The tool shown in Figures 4 and 5 is operable somewhat in the manner of the tool shown in Figures 1 to 3. As before, the post 31 may be adjusted to approximate position by rotating the threaded portion thereof in the threaded opening of cross-member 30. While the jaws of the gripping element are held in spaced-apart relation by yieldingly urging the finger grips 50, 50 toward the handle 32, the end of the post 31 in association with the jaws may be placed against the end of battery post P'. Upon releasing finger grips 50, spring 36 will urge pivot block 35 away from the cross-member, whereby the links 43 and 44 will swing the arms or extensions 39^b and 40^b inwardly in an arc about the pivot 37 to engage the toe portions 39^a and 40^a of the gripping elements under the lower edge portions of the terminal T'. When the tool is properly positioned, as shown in Figure 4, further rotation of the pressure post 31 to urge cross-member 30 in the direction toward handle 32 will apply heavy opposing pressure between the end of post 31 and the toe portions 39^a and 40^a of the gripping elements to loosen terminal T' from post P'.

Thus has been provided a simple compact and yet powerful pulling tool for removing corroded terminals from battery posts. The tools shown and described are easy to operate, in each case the gripping elements thereof being substantially self-adjusting to a substantially wide range of battery terminal sizes.

Modifications of the invention may be resorted to without departing from the spirit thereof or the scope of the appended claims.

What is claimed is:

1. A tool of the class described comprising a cross-member having an opening therein, an internally threaded nut received through said opening to be rotatable relatively of said cross-member, a pressure post threaded at one end into said internally threaded nut, said nut thereby being rotatable in said cross-member to adjust said post axially relatively of the cross-member, said post having a longitudinal slot therein, an element slidably received through said slot to be slidable relative to said cross-member, a pair of oppositely disposed gripping jaws pivoted in crossed relation on said element to provide gripping portions in association with the end of said post remote from said cross-member and providing extensions outwardly of said post, and pivoted links extending between said cross-member and said extensions of the gripping elements.

2. A tool of the class described comprising a cross-member, an internally threaded nut, means for mounting said nut to be rotatable relatively of said cross-member without relative axial movement, a pressure post threaded at one end into said internally threaded nut, said nut thereby being relatively rotatable in said cross-member to adjust said post axially relatively of the

cross-member, an element axially slidably mounted on said post to be slidable toward and from said cross-member, a pair of oppositely disposed gripping members pivoted in crossed relation on said element to provide gripping portions in association with the free end of said post and to provide outward extensions, and links pivotally connected between said cross-member and said extensions of the respective gripping members.

3. A tool of the class described comprising a cross-member having a threaded opening therein, a pressure post axially adjustably threaded in said opening, means for relatively turning said post and said cross-member to provide relative axial adjustment between the same, an element axially slidably mounted on said post to be slidable toward and from said cross-member, a pair of oppositely disposed gripping members pivoted in crossed relation on said element to provide gripping jaws in association with the free end of said post and to provide integral outward extensions, pivoted links extending between said cross-member and said outward extensions of the respective gripping members, and yielding means extending between said cross-member and said slidably element for yieldingly urging the same apart.

4. A tool of the class described comprising a cross-member having a threaded opening therein, a pressure post adjustably threaded in said opening, means for relatively turning said post and said cross-member to provide relative axial adjustment between the same, an element axially slidably mounted on said post to be slidable toward and from said cross-member, oppositely disposed pivot pins on said slidably element, a pair of oppositely disposed gripping members pivoted in crossed relation on said pivot pins to provide gripping jaws in association with the free end of said post and providing outward extensions, links pivotally connecting between said cross-member and said outward extensions of the respective gripping members, yieldable means ex-

tending between said cross-member and said slidably element for yieldingly urging the same apart, and finger grips non-rotatably secured on said pivot pins outwardly of said gripping elements.

5. A tool of the class described comprising a cross-member having a central internally threaded portion, a pressure post threaded at one end through said internally threaded portion, means for relatively rotating said post and said threaded portion with respect to each other to provide axial adjustment of the post relative to the cross-member, an element axially slidably mounted on said post to be slidable thereon toward and from said cross-member, a pair of oppositely disposed gripping members pivoted intermediate the ends thereof to said element to provide oppositely disposed gripping jaws in association with the free end of said post and to provide oppositely disposed arms extending outwardly of opposite sides of said post, and a pair of links each pivotally connected at one end thereof to said cross-member and at the other end to the one of said oppositely disposed arms.

6. A tool of the class described comprising a cross-member having a central internally threaded portion, a pressure post threaded at one end through said internally threaded portion of the cross-member, means operable for relatively rotating said pressure post and said threaded portion with respect to each other to adjust the post axially relatively of the cross-member, an element axially slidably mounted on said post intermediate the other end thereof and said cross-member to be slidable toward and from the cross-member, a pair of oppositely disposed gripping members pivoted in crossed relation on said slidably element to provide gripping portions in association with said other end of said post and to provide outward extensions, and links pivotally connected between said cross-member and said extensions of the respective gripping members.

ARTHUR P. STONE,
